UNITED STATES PATENT OFFICE

WILLIAM H. RAMSEY, OF CORPUS CHRISTI, TEXAS

SIGN

Application filed November 16, 1928. Serial No. 319,936.

The invention relates to a sign such as generally employed by a merchant to indicate the character of goods offered for sale, or other data, or information to be conveyed to the public.

The invention provides a sign which both actually displays the goods and conveys information by legend or symbol.

In accordance with the invention the sign 10 contemplates a frame having the outline of a letter, or other symbol, or legend and constructed to hold the articles which are dealt in by the merchant and thus actually displayed.

15 While the drawing illustrates a preferred embodiment of the invention, it is to be understood that in adapting the means to meet specific needs and requirements, the design may be varied and such other changes in 20 the minor details of construction may be resorted to within the scope of the invention as claimed, without departing from the spirit thereof.

25 For a full understanding of the invention and the merits thereof, reference is to be had to the following description and the drawing hereto attached, in which:—

Figure 1 is a front view of a sign illustrative of an embodiment of the invention.

30 Figure 2 is a rear view showing the parts on a larger scale.

Figure 3 is a sectional view on the line 3—3 of Figure 1, looking to the right as designated by the arrows.

35 Figure 4 is a detail perspective view of a modification.

Figure 5 is a sectional view taken transversely through the modified form shown in Figure 4.

40 Corresponding and like parts are referred to in the following description and designated in the several views of the drawing by like reference characters.

45 The sign may consist of a legend, or symbol, such as a single unit, or a number of

units, as letters, grouped to form a word. The symbol, or letter, includes a frame 1 which may have any outline or shape. The frame is hollow and adapted to receive the goods or merchandise to be displayed and 50

which may consist of fruit, nut, candies and sundry small articles capable of occupying a small space. The frame 1 may be of any construction and of a size to hold an appreciable number of the articles to be exhibited. The frame may consist of wire 55

fabric, or may embody sheet material of any nature in which event the back and sides of the frame will be closed and the front open to display the goods. The open front of 60 the frame may be closed by wire fabric to retain the goods in place and yet admit of ready observation of the goods. The goods are readily removable from the frame to admit of replacement or substitution of 65

goods of a different nature. When fruit is displayed apples, oranges, lemons and the like are placed within the frame. Nuts, candies, cigarettes and other small articles may likewise be advantageously displayed. The 70 wire fabric closing the front of the frame may be attached in any manner to admit of ready replacement of the goods as occasion may require. The front of the frame may be closed in any determinate way to 75 retain the goods in place without obstructing the view thereof.

When the sign embodies a number of letters grouped to form a word, as indicated in Figure 1 of the drawing, the several units 80 or symbols are connected by wires 2 engaging staples 3 applied to the back of the letters or symbols. When the back of the frame is solid it will be provided with a plurality of openings 4 to insure ventilation which is essential when the goods on display are of a perishable nature, such as fruit and vegetables.

In the modification shown in Figures 4 and 5 the frame 1 is open at one end to ad- 85 90

mit of the goods being readily placed in position or removed from the frame. The numeral 5 designates a bar which extends across the open end of the frame to retain the goods in place. The ends of the bar 5 are reduced and engage staples 6 applied to the extremities of opposite sides of the frame. To remove the bar 5 it is moved longitudinally to disengage one end from a staple 6 after which it is moved in the opposite direction to disengage the opposite end from the other staple. After the frame 1 has been supplied with the goods to be displayed one end of the bar 5 is engaged with a staple 6 after which the opposite end of the bar is engaged with the other staple, as will be readily understood. Flanges 7 extend inwardly from the side walls and provide wide surfaces against which the wire fabric closing the front of the frame may be firmly secured. The flanges will also constitute abutments to limit outward movement of large fruit placed in the frame.

When the frame 1 is formed from sheet metal, this being the preferable construction, the wire fabric closing the front is soldered thereto. An opening is left or formed in the top of the frame for introducing or removing the goods and may be closed if desired. This opening is designated by the numeral 8 in Figure 1.

Having thus described the invention, I claim:

1. A sign comprising a series of symbols and means to support the same in operative relation to each other, said symbols each consisting of a frame open at the front and having the outline of the required symbol and adapted to receive loose goods to be displayed, and a wire fabric closing the front of the frame to retain the goods therein and admit of ready observation thereof.

2. A sign comprising a frame having the outline of the required symbol or legend, and adapted to receive the goods to be displayed, said frame being open at its front and at one end, a foraminous closure for the open front of said frame, a bar adapted to extend across the open end of the frame and having reduced ends resting upon walls of the frame at opposite sides of the open end of the frame, and staples extending from the opposed walls of the frame to engage the ends of the bar and retain it in place.

3. A sign comprising a series of symbols and means to support the same in operative relation to each other, said symbols each consisting of a frame having the outline of the symbol and adapted to receive loose goods to be displayed, the front of the frame being open and the frame having inwardly extending flanges about the margins of its open front, and wire fabric for closing the open front of said frame having its marginal

portions secured against the outer faces of said flanges.

4. A sign comprising a series of symbols and means to support the same in operative relation to each other, said symbols each consisting of a frame open at the front and having the outline of the required symbol and adapted to receive goods to be displayed, the frame being formed with ventilating openings, and a wire fabric closing the front of the frame to retain the goods therein and admit of ready observation thereof and permit air to enter the frame.

In testimony whereof I affix my signature.
